CLAIM

The ornamental design for an oven, as shown and described.

DESCRIPTION

This application is related to U.S. application Ser. No. 17/490,442, filed Sep. 30, 2021, the entire disclosure of which is hereby incorporated herein by reference.

FIG. 1 is a top-front-left perspective view of an oven showing our new design according to a first embodiment; FIG. 2 is a bottom-front-left perspective view of the first embodiment;

FIG. 3 is a front elevational view of the first embodiment; FIG. 4 is a rear elevational view of the first embodiment; FIG. 5 is a left side elevational view of the first embodiment; FIG. 6 is a right side elevational view of the first embodiment;

FIG. 7 is top plan view of the first embodiment; FIG. 8 is a bottom plan view of the first embodiment;

FIG. 9 is a top-rear-right perspective view of the first embodiment;

FIG. 10 is a bottom-rear-right perspective view of the first embodiment

FIG. 11 is a top-front-left perspective view of an oven showing our new design according to a second embodiment; FIG. 12 is a bottom-front-left view of the second embodiment;

FIG. 13 is a front elevational view of the second embodiment;

FIG. 14 is a rear elevational view of the second embodiment; FIG. 15 is a left side elevational view of the second embodiment;

FIG. 16 is a right side elevational view of the second embodiment;

FIG. 17 is top plan view of the second embodiment;

FIG. 18 is a bottom plan view of the second embodiment;

FIG. 19 is a top-rear-right perspective view of the second embodiment; and,

FIG. 20 is a bottom-rear-right perspective view of the second embodiment.

The oven illustrated in FIGS. 1-20 may be, for example, a pizza oven or another type of oven.

The broken lines in the drawings depict portions of the oven that form no part of the claimed design.

1 Claim, 20 Drawing Sheets
